LOOM SHUTTLE

Harold E. Goff, Millbury, Mass., assignor to Watson-Williams Manufacturing Company, Millbury, Mass., a corporation of Massachusetts

Application April 15, 1940, Serial No. 329,694

2 Claims. (Cl. 139—208)

This invention relates to loom shuttles of the type in which a bobbin is mounted on a spindle pivoted in the shuttle body and yieldingly held in either loading or running position.

5 It is the general object of my invention to provide an improved and simplified construction in shuttles of the defined type, to the end that economy in manufacture and reliability in operation may be satisfactorily attained.

10 A more specific object of the invention relates to the provision of improved means for preventing a bobbin from shifting axially of a spindle during loom operation. I also provide improved means for defining the running position of the bobbin on the spindle.

15 My invention further relates to arrangements and combinations of parts which will be hereinafter described and more particularly pointed out in the appended claims.

20 A preferred form of the invention is shown in the drawing, in which

Fig. 1 is a partial plan view of a shuttle embodying my improvements;

25 Fig. 2 is a sectional side elevation, taken along the line 2—2 in Fig. 1;

Figs. 3 and 4 are detail sectional side elevations, showing certain parts appearing in Fig. 2 but in different operative relations;

30 Fig. 5 is a side elevation of a bobbin guiding and holding member;

Fig. 6 is a plan view thereof; and

Fig. 7 is an end elevation thereof.

Referring to the drawing, I have shown a portion of a shuttle body S having its inner portion cut away as indicated at 10 to receive a bobbin B mounted on and supported by a spindle 12. A combined guiding and holding member 15 is secured in a recess 16 in the shuttle body S and is held in place by a pin 17 and a screw 18, 35 which holding parts pass through aligned transverse holes 19 and 20 (Fig. 5) in the body S and member 15.

The spindle 12 has a head 22 of such width as to fit snugly between the upright sides 24 of the member 15. The head 22 is also provided with a notch or recess 25 which may be hooked over the screw 18 to form a pivot for the spindle 12.

40 A spring plate 33 is positioned in a relatively shallow recess 34 in the shuttle body S and is tensioned and drawn downward by a screw 35 which is threaded in a nut 36 inserted in a recess 37 in the bottom of the shuttle.

45 Engagement of the spring 33 with a corner lug 38 on the spindle head 22 holds the spindle

12 yieldingly in the raised loading position shown in Fig. 3 or in the lowered running position shown in Fig. 4. It will be noted that in the raised position the corner lug 38 is at one side of the vertical plane of the pivot screw 18, while 5 in the running position shown in Fig. 4 the corner lug 38 is well to the right of the vertical plane through the screw 18. When in lowered position, a projection 40 of the spindle head 22 engages the pin 17 and thus determines the exact 10 running position of the spindle.

The bobbin guiding and holding member 15 is provided, in addition to the side portions 24, with an end or holding portion 44 having a substantially semi-circular recess 45 in its upper edge. 15 The front corners of the side portions 24 are also formed in cam surfaces as indicated at 47, for a purpose to be now described.

With the spindle 12 in the raised position shown in Figs. 2 and 3, a bobbin B may be placed 20 on the spindle as shown in Fig. 2 and may be forced downward until the flange 50 at the base of the bobbin engages the curved cam surfaces 47 on the member 15, which surfaces then form a stop or abutment and determine the inmost 25 position of the bobbin.

As the spindle 12 is then swung down to the position shown in Fig. 4, the flange 50 remains in engagement with the surfaces 47 and is guided thereby into the opening 52 between the ends 30 of the side portions 24 and the end portion 44 of the member 15.

When the spindle has been moved down to running position, as indicated in Fig. 4, the flange 50 is seated snugly in the recess 52. Axial 35 displacement of the bobbin B on the spindle 12 is thus effectively prevented.

It will be noted that the member 15 may be formed from a single piece of metal by simple press and punch operations, and that the cam 40 surfaces 47 make it unnecessary to provide a flange or shoulder on the spindle 12 to act as a stop for the bobbin B, as has been the usual prior practice.

Having thus described my invention and the advantages thereof, I do not wish to be limited to the details herein disclosed, otherwise than as set forth in the claims, but what I claim is:

1. For use with a loom shuttle having a pivoted spindle adapted to receive a flanged bobbin; a bobbin holding member formed from a single blank of sheet material and comprising a bottom portion, upturned side walls integral with the bottom portion between which the spindle is adapted to be pivotally mounted, and 55

- an end portion extending from the bottom portion and including an upturned flange spaced slightly from the ends of the side walls and recessed to receive the flanged end of the bobbin,
5 the upper portions of the ends of the side walls being provided with cam surfaces arranged to guide the bobbin flange into the space between the upturned end flange of the holding member and the ends of the side walls as the spindle is
10 swung about its pivot from the bobbin receiving position to the running position.
2. In a loom shuttle having a pivoted spindle supporting a bobbin with a flanged end, in combination, a bobbin-holding member having a
15 bottom portion, spaced side portions joined to-

gether by said bottom portion and between which side portions said spindle is mounted, said bottom portion having a forwardly and upwardly projected forked and recessed end portion spaced from the front edges of said side portions, and means to secure said holding member and spindle in said shuttle, the front edges of said side portions each having a cam face and said edges being effective to engage and limit inward movement of a bobbin on the spindle, and 10 said forked and recessed end portion engaging the outer face of the flange on said bobbin and preventing outward movement of the bobbin on said spindle. 5

HAROLD E. GOFF. 15
